TABULATING MECHANISM FOR TYPE-WRITERS AND LIKE MACHINES

Walter T. Sagner, West Hartford, Conn., assignor to Underwood Corporation, New York, N. Y., a corporation of Delaware

Application December 8, 1950, Serial No. 199,840

5 Claims. (Cl. 197—178)

1

This invention relates to tabulating mechanisms for typewriters and like machines, and has reference particularly to such mechanisms wherein the tabulator reeds are spring projecting and power retracted.

In tabulating mechanisms of this kind, exemplified in the Yaeger Patent No. 2,384,060, depressing any tabulator key will release a corresponding reed for spring projection and also release the carriage for a tabulating run, all occurring although the power of the machine is shut off. In that retraction of the thus released reed and the resultant restoration of the carriage to letter-feed control depend for operation on the motor power of the machine, the carriage cannot be returned to its previous position until the motor switch of the machine is again turned on and the normal condition of the tabulating mechanism is thus restored.

While the above difficulties may be had by inadvertent operation of the usual decimal tabulator keys, the difficulty more frequently arises with typewriters equipped with a palm tabulator key. For instance, in merely placing the dust cover on the machine at night, the typist may readily hit the palm key, which would immediately tabulate the carriage to a laterally projecting position from which same may not be returned unless the motor power is again turned on.

Accordingly one of the objects of the invention is to obviate the foregoing difficulties by providing a locking means preventing effective operation of the tabulator keys unless the motor switch of the machine is in its "on" position.

Another object is to provide, in a tabulating mechanism wherein the reed or reeds are spring-projected and power-restored, means under control of the motor switch and effective in the "off" position thereof, to block operation of the power means and thereby prevent spring projection of said reeds.

In its more specific aspect the invention concerns power tabulating mechanisms of the kind shown in the said Yaeger patent, No. 2,384,060, an object being to prevent inadvertent operation by the decimal tabulating keys or the palm key when the switch controlling the electric motor of the machine is in "off" position.

With the above and other objects in view the invention will now be described with reference to the accompanying drawings wherein one embodiment which the invention may assume in practice is shown for purposes of illustration.

In the drawings,

Fig. 1 is a perspective view of the tabulating mechanism embodying the invention.

Fig. 2 is a fragmentary elevational view of the mechanism shown in Fig. 1, as viewed from the right hand side, the locking device being in

2

its ineffective position corresponding to the "on" position of the motor switch.

Fig. 3 is a view similar to Fig. 2 but with the locking device in its effective position corresponding to the "off" position of the switch, and

Fig. 4 is a fragmentary front elevation of that portion of the mechanism for controlling carriage return, in the condition of effecting a power carriage return and with the motor switch on.

10 The present invention is shown in the drawing in the manner in which it may be applied to a power tabulating mechanism of the kind shown in the Yaeger Patent No. 2,384,060. Only a brief showing of the mechanism of the Yaeger patent is given herein, reference being had to said patent for a more detailed disclosure.

Referring to Fig. 1, a platen carriage is supported by means including a rail 7 for travel on the mainframe of the typewriter in letter-feed and return directions. The carriage is moved in letter-feed direction by the usual spring drum 8 connected by a draw band 9 to the carriage. The usual letter-feed mechanism is provided, of which only the escapement wheel 10 and a feed-dog 11 are herein shown. The escapement wheel 10 is operatively connected to the platen carriage 6 by means including a pinion 12 and gear rack 13, the latter being on the carriage. The dog 11 is the one of the usual two feed-dogs 20 which, in the inactive condition of the feed mechanism, is engaged with the escapement wheel. The two feed-dogs are carried on a dog rocker, not shown, and are thereby brought alternately into coaction with the escapement wheel to effect the step-by-step feed, in the well-known manner. The dog 11 is pivoted on the dog rocker and is spring-urged toward engagement with the escapement wheel 10 and, to free the carriage for a tabulating run, may be swung clear of said wheel by a lever 14 operated by means later described.

Carriage return may be actuated by power-operated mechanism such as that partly shown in Fig. 4, which corresponds substantially to that fully disclosed in my co-pending application, Serial No. 27,224, filed May 15, 1948, now Patent No. 2,541,295, issued February 13, 1951. Referring to Fig. 4, an electric motor, not shown, continuously rotates a gear 15 carried on a spindle 16. The gear 15 has clutch teeth with which like teeth of a clutch collar 17 engage to effect a driving connection to a drum 18, to which collar 17 is slidably splined. The drum 18 and collar 17 are journaled on but rotatable independently of spindle 16. A draw-band 20 around the drum 18 extends therefrom over suitable guide means and is connected at its other end to the carriage 6. An encased spiral spring 21 tends to rotate the drum 18 in the direction such as to maintain the draw-band 20 constantly taut

during all movement of the carriage. The clutch collar 17 is shiftable into and out of driving engagement with gear 15 by a fork 22 engaging a groove of said collar and supported on a rock-shaft 23. Also secured to said shaft is an arm 24 connected by a link 25 to a carriage-return clutch-control lever 26 pivoted at 27. A spring 28 acting on arm 24 tends to slide collar 17 to clutch-engaging position, and thereby tends to swing the control lever 26 upward about pivot 27, in which position said parts are shown in Fig. 4, effecting carriage return.

As shown, the clutch-control lever 26 is in the tripped or released position, which it assumes in order to close the carriage-return clutch. With the carriage-return clutch open or disengaged, the control lever 26 is in a lower position as indicated by the dot-and-dash outline of its end portion in Fig. 4. Lever 26 is releasably retained in said lower position by a latch device comprising primary and secondary latches 29 and 30, operated to release lever 26 by depressing a carriage-return key, as disclosed in my said co-pending application. The operative connection of the carriage-return key to latches 29, 30 is such that as the key is depressed, primary latch 29 moves rearwardly, or rightwardly as viewed in Fig. 2, and thus releases control lever 26 to the force of spring 28. The secondary latch 30 is idle under this condition and becomes effective only in the event that the termination of carriage-return swings lever 26 down and yet the latch 29 has not been restored because the carriage-return key is held depressed. In such instance the secondary latch 30 temporarily holds the lowered lever 26 until release of the carriage-return key allows the primary latch 29 to take over. The restoration of control lever 26 to its lower, inactive position, automatically incident to completion of carriage return, is effected by mechanism, not shown herein, forming part of the subject matter of my said co-pending application. Said mechanism becomes effective when a carriage-return limiting stop 31, Fig. 1, engages and moves a counterstop, not shown. The stop 31 is one of the two conventional margin stops carried on a rack bar 32 on the carriage 6.

The electric motor which, as stated, furnishes the power for the carriage-return mechanism, may also actuate other mechanisms of the typewriter, such as the type actions, case-shift mechanism, etc. The operating means for these various power-operated mechanisms usually includes a constantly rotating drive element, herein shown as a snatch roll 33, Fig. 1, connected by suitable power-transmitting means to the motor.

In the electric circuit of said motor is a snap switch 35, Fig. 1, having an operating arm 36 operable from the front of the machine by a control element or knob 37. The knob 37 is fast on a stub shaft 38 which carries at its inner end a slotted arm 40. The slot of arm 40 engages the crank end 41 of a shaft 42. The rear end of the crank shaft carries a plate 43 provided with a stud 44 into a socket of which the ball end of switch arm 36 extends. The coaction of the stud 44 with the switch arm 36 is such that turning the knob 37 rightward from the "off" position of Fig. 1 closes the snap switch 35 and turning the knob leftward opens the switch. The plate 43 has articulated to a prong 45 thereon a rightwardly extending rod 46 which near its right end is slidably guided in a hole 47 in a tabulator housing 48, Fig. 2. An angular end 49 of the rod 46 overlies the clutch-control lever 26 and is

guided in a transverse slot 50 of a bracket secured to fixture 48. With the switch 35 in the "off" position as in Fig. 1, the rod end 49 coacts with the adjacent inclined edge of the clutch-control lever 26 so that the rightward end thereof is held lower than the shoulders of both the latches 29 and 30, see Fig. 3. This position of the control lever end in relation to said latch shoulders is of importance, also, with respect to the motor-switch control of the locking device of the tabulator mechanism, later described. With the switch in "off" position and the end of lever 26 therefore held down, as described, it follows that no power carriage return may be instituted by operation of the carriage-return key. This feature forms part of the subject matter of the Helmond Patent No. 2,366,107.

In that the power-operated tabulating mechanism, now to be described, is like that shown and described in detail in the Yaeger patent, No. 2,384,060, only a brief description will be given. Referring to Fig. 1, a tabulator rack 52 at the rear of the carriage 6 carries a series of stops 53, each of which is settable downwardly to an effective position for cooperation with the raised one of a group of denominational tabulator reeds 54. The reeds are slidably supported in the housing 48 for up and down shifting, and each reed has a spring 55 urging same upwardly. Each reed also has a forwardly extending shoulder 56 which is pressed by spring 55 into engagement with a cross bar of a bail-like frame 57, rockable on a shaft 58 and urged to swing counterclockwise by a spring 60. The bail frame, forward of its pivot 58, includes a rod 61 which by a link 62 connects the bail frame 57 to an arm 63 secured to a shaft 64 which also has secured thereto a second arm 65. The force of spring 60 on the bail frame 57, transmitted to arm 65, tends to swing same forward. Blocking of the forward swing of arm 65 prevents the rocking of bail frame 57 and thus retains each tabulator reed 54 against being raised by its spring 55. The blocking of arm 65 and therefore the bail frame 57 is effected by a latch lever 66 abutting a bent-off end of said arm. By mechanism later described, the depression of any tabulator key 67 will rock the latch lever 66 about its pivot 68 and thereby unblock the arm 65, thus allowing bail frame 57 to be swung counterclockwise by its spring 60. The tabulator reed 54 which has been selected for raising by means later described is thus permitted to be raised by its spring 55.

The means for selectively releasing a certain one of the tabulator reeds 54 for projection by depressing a selected tabulator key 67 includes mechanism operating on the permutation principle. Each tabulator key 67 is on a lever 70, an upstanding arm 71 of which swings forwardly on depressing the key. The arm 71 thus forwardly moves a selected one or two of a set of four slides 72, determined by an arrangement of notches in the slides in accordance with the permutation system, and moves the slide or slides forwardly. An equalizing mechanism comprising two coating levers 73 for each slide 72 assures fore-and-aft movement of the slides in a parallel, rectilinear motion. Each slide 72 is operatively connected by a Bowden wire cable 74 to a bell crank 75 at the rear of the machine so that when the selected one or two slides move forwardly a corresponding one or two of the bell cranks 75 is rocked clockwise. Said bell cranks individually shift laterally-slidable blades 76 leftwardly against the force of their restoring

springs 11. The bottom edges of said blades 16 are notched in accordance with the permutation system, so that by shifting selected blades the notches of each blade are aligned with each other beneath only one of the tabulator reeds 54 and thus allow said reed to be spring-raised.

The above described function of bail frame 57 and associated mechanism, that of preventing raising of the tabulator reeds 54, serves primarily in conjunction with tabulating operations effected by a palm tabulator key, later described. The principal function of the bail frame 57 is that of a universal member to power-retract or restore the raised reed, as presently described. Said bail frame in its swinging action, incident to raising a reed, also acts to release the carriage to a tabulating run by swinging the escape- 10 ment dog 11 free of wheel 10, for which purpose the bail frame 57 is connected by a pin-and-slot connection 80 to the mentioned lever 14.

The mechanism for power-operating bail frame 57 is as follows: Adjacent the arm 65 the shaft 64 has another arm 81 to which a link 82 is connected. Said link has a pin-and-slot connection 83 to a power actuator 84 movably supported at its forward end by an arm 85. The actuator 84 is urged by a spring 86 in an upward and rearward direction to an extent determined by stop means, not shown. The actuator 84 pivotally carries a drive pawl 87 cooperating with, but 20 normally free of, the snatch roll 33.

To effect power actuation of the bail frame 57, the actuator 84 is drawn downwardly against the force of spring 86 by means later described. During the downward movement of actuator 84 the pawl 87 becomes engaged with the snatch roll 33 and, after limitedly rocking about its pivot, moves the actuator forward until a lug 88 thereon co-acts with the snatch roll 33 to raise the actuator and thus disengage the pawl from the snatch roll. This forward movement of the actuator 84, transmitted through the link 82 and arm 81, rocks the shaft 64 which, through arm 63 raises link 62 and thus rocks the bail frame 57 clockwise. The bail frame 57, in restoring the raised reed 54 to its normal position, thus assumes its position as shown in Fig. 1 from which it had been swung by the raising action of the reed. It will be seen that the bail frame 57, the operating train 61-64 connected thereto and the power-actuated device 84-85 constitute a power-operated retracting means for the tabulator reeds 54.

It will be noted that the start of the tabulating operation, incident to which the selected reed was raised, was instituted by depressing one of the tabulator keys 67, and this in turn swung the latch lever 66 clear of the arm 65. The release of the tabulator key allows latch lever 66 to be restored to its normal position where, upon completion of the power actuation of bail frame 57 as above described, said latch lever re-engages arm 65, to hold the bail frame and associated mechanism connecting the frame to the power actuator 84, in its normal or inactive position.

The operation of latch lever 66 by the tabulator keys 67 is effected incident to the forward sliding of the blades 12. At their rightward ends said blades each have a shoulder 90 adapted to actuate an upstanding arm of a bell-crank lever 91, the other arm of which engages a lever 92, which in turn engages the forward end of latch lever 66. Lever 92 extends rightwardly from the point of engagement with lever 66 in a prong 93 at which point a leverage train, in-

cluding a palm tabulator key, engages lever 92 for operating latch lever 66.

The palm tabulator key mechanism, not shown herein, may be as shown and described in said Yaeger patent. It may be here noted that, because the palm-key mechanism in said patent operates independently of the tabulator-reed selecting mechanism, one of the reeds 54 is to be released without operating the selecting mechanism. That is, one of the reeds should be released solely by the swinging of the bail frame 57 as effected by release of the arm 65 from control by latch lever 66. Accordingly the leftmost tabulator reed 54, associated with the tabulator key 67 of the "cents" denomination is adapted for release also by the palm key, this being accomplished in the manner clearly set forth in said Yaeger patent.

As described in said Yaeger patent, the tabulator reeds 54 are limitedly movable leftwardly from their normal positions and this movement is employed to initiate a power operation of the retracting mechanism. Thus, a projected reed, upon being engaged by a set tabulator stop 53 during the then ensuing tabulating run, is caused to be laterally moved slightly. This in turn initiates the power operation of the restoring bail frame 57, so that the projected reed becomes automatically restored. An upright arm of a three-arm lever 94 is engaged by the leftmost reed 54. Lever 94 is pivoted at 95 and is connected by a link 96 to a second lever 97 fulcrumed on shaft 58 and, from lever 97, is connected by a link 98 to a bail 100. The rightward portion of bail 100 has a pin-and-slot connection 101 to a power-tripping lever 102 pivoted at 103 and urged by a spring 104 to swing clockwise. The force of spring 104, transmitted through the operating train just described, tends 20 to rotate the three-arm lever 94 clockwise about its pivot 95 and thus presses the group of reeds 54 to the normal rightmost position. The lever 102 carries a hooked member 105 which, upon swinging said lever counterclockwise, becomes engaged with a lug 106 on the actuator 84, causing same to be lowered and thus initiate a power operation of the restoring bail frame 57, as previously described. The connection of the hooked member 105 to lever 102 and the manner in which said member operates, and thereafter becomes disengaged from, the power actuator 84 are well known and need not be here described.

The latch lever 66 has a latch 107 pivoted thereon, said latch being spring-pressed clockwise, with its rightward portion normally against the bottom of lever 66. When an operated tabulator key 67 or the palm key is held depressed, latch 107 prevents a repeat tabulation by temporarily latching arm 65 in its normal position as said arm reaches that position incident to conclusion of a power operation of the reed-restoring bail frame 57. In this way bail frame 57 is prevented from again swinging upward by its spring 60, which would again release the carriage 6 and again project the reed 54 which had been selected by the depressed tabulator key. As soon as the operated key is released, the latch lever 66 returns to its normal position shown in Fig. 1 and thus resumes control of the reed-restoring mechanism by re-engaging arm 65.

The various mechanisms described up to this point form the subject matter of or are disclosed in several prior patents, with the exception of the mechanism for automatically termi-

nating power-return of the carriage, which mechanism forms part of the subject matter of my co-pending application, Serial No. 27,224, now Patent No. 2,541,295, issued February 13, 1951. As aforeindicated, the principal related patent is that to Yaeger, No. 2,384,060, in the power tabulating mechanism of which the locking means of the present invention is particularly useful and advantageous. It will be recalled that in said patent the tabulator reeds are spring-projected and power-retracted, as herein described. The other related patent is that to Helmond, No. 2,366,107, referred to in regard to the mechanism for manually operating the motor switch and in regard to the operative connection between this switch and the carriage-return clutch-control lever 26. It will be observed as the description of the present invention proceeds that the clutch-control lever 26 and the motor-switch operating mechanism, with its operative connection to said lever, form a substantial part of the mechanism embodying the present invention.

The mechanism associated with the motor-switch operating means 37—44 and the clutch-control lever 26, by which effective operation of the tabulator keys is prevented while the motor switch is off, will now be described. It will be recalled that the clutch-control lever 26 is latched in a down position as shown in Fig. 1 by the primary latch 29 and that said lever remains in substantially that position during all operations of the machine occurring incident to typing, moving therefrom only to institute carriage return. It will also be recalled that under certain conditions, when they occur at the completion of carriage return, the secondary latch 30 will temporarily hold lever 26 until that condition is eliminated, after which the primary latch 29 again assumes control of said lever. For reasons explained in Helmond patent, No. 2,262,676, it is necessary that the latching shoulder of the secondary latch 30 be slightly lower than the shoulder of primary latch 29, see Fig. 2. To enable the secondary latch to engage lever 26, said lever must in terminating carriage return be lowered sufficiently to have said latch hook over same. Thus the clutch-control lever 26, although remaining under non-operative control by the primary latch 29, is capable of slight up and down movement at its latched end. It will be observed that this slight movement occurs also in response to operating the motor switch 35 between "on" and "off" positions. The upper position of lever 26, Fig. 2, in which its lever end portion is against the shoulder of latch 29, is assumed when the motor switch 35 is in the "on" position and the lower position of lever 26, Fig. 3, is assumed when said motor switch is in the "off" position. Referring to Fig. 1 it will be evident that these two positions of clutch-control lever 26 in its non-operative state result from the camming action of the angular end 49 of rod 46 on the inclined edge of said lever. This slight movement of lever 26 is employed to control the locking device now to be described.

The shaft 64, forming a part of the mechanism by which the bail frame 57 is operated to power-restore the reeds 54, has at its rightward portion a C-shaped arm 113 secured thereto, the upper end of which provides a laterally extending lug 111. On a bracket 112 secured to the mainframe of the typewriter a locking lever 113 is pivoted by a stud 114. To permit lever 113 to yield under certain conditions, said lever

is constructed of two parts 115 and 116. The two parts overlap and both parts are supported on the pivot stud 114. A spring 117 tensioned between upreaching arms on the two lever parts tends to rotate part 116 clockwise toward part 115, but is blocked from such relative movement by an adjustable eccentric 118 on part 116 engaging an arm 120 on part 115. The two-part yieldable construction of lever 113, however, enables it to yield when the part 115 is rotated clockwise and part 116 is blocked against movement. The lever part 115 has a rearwardly projecting arm extending beneath the end portion of the clutch-control lever 26. The two-part lever 113 is urged by a spring 121 to swing counterclockwise, the spring being connected to the lever part 116 and anchored on bracket 112. The spring 117 is to be substantially stronger than spring 121 so that the two-part lever 113 will not yield under the restoring force of spring 121. In its normal or unoperated position, Fig. 2, the part 116 of lever 113 rests against a stop lug 122 on said bracket. The leftward portion of lever part 116 has two bent-off portions forming right-angularly related faces 123 and 124 extending laterally from said lever part.

The operation of the locking device comprising the two-part lever 113 will now be described. It will be recalled that as a tabulating operation is initiated, the latch lever 66 is swung counterclockwise free of the lug of arm 65 to thus allow the bail frame 57 to rock counterclockwise and thereby permit a selected reed 54 to be raised. During this action the shaft 64 rocks clockwise as viewed in Fig. 2 and the C-shaped arm 110, swinging therewith, advances its lug 111 past the face 123 of lever part 116. The lever face 123 is out of the path of lug 111 because the two-part lever 113 is in its normal position, Fig. 2, which it assumes under the force of its spring 121 when the clutch-control lever 26 is in its upper position against the shoulder of latch 29. This upper position of lever 26 is assumed when said lever is not influenced by the camming action of the rod end 49, the rod 46 being at a rightward position as viewed in Fig. 1 because the motor switch 35 is turned on. It will now be seen that a tabulating operation, initiated by rocking the latch lever 66, will progress to completion through the several phases of operation above described, as long as the motor switch 35 is turned on, with the control knob 37 thereof in the "on" position.

When the motor switch 35 is turned off by rotating its control knob 37 to the "off" position, the resultant leftward shifting of rod 46 causes its angular end 49 to cam the clutch-control lever 26 downward so that its lower end assumes the position shown in Fig. 3. During this downward movement, lever 26 actuates the two-part lever 113, swinging same clockwise about its pivot 114 so that the face 123 thereof moves into the path of arm lug 111. By thus blocking movement of arm 110, a tabulating operation is prevented, although the depression of the tabulator key has swung latch lever 66 clear of arm 65. The effect of this blocking of arm 110, operating through shaft 64, arm 63 and link 62, is to prevent the bail frame 57 from rocking counterclockwise, thus preventing the rise of any of the tabulator reeds 54. In that the operation of this train of mechanism is necessary to initiate any tabulating operation, the blocking of same as described prevents a tabulating operation from occurring, whether it be initiated

by the decimal tabulator keys or the palm key. The face 124 on lever 113 obviates the chance of the lug 111 becoming caught in back of face 123, in the event that the motor switch 35 should be turned off immediately after a tabulating operation has begun. In such instance the C-shaped arm 110 will have swung rightward so that its lug 111 has moved past the face 123 while the two-part lever 113 is still in the Fig. 2 position. Turning the motor switch off at that instant and thereby rocking lever 113 toward the Fig. 3 position would bring the lug of face 123 up in back of the lug 111, where it would obstruct the subsequent return of arm 110. It will be seen that the provision of the face 124 prevents this condition from arising. That is, as lever 113 swings clockwise, its face 124 will engage the lower edge of lug 111. The blocking of lever 113 at face 124 in this manner will cause said lever to yield, by further tensioning spring 117, which condition will prevail until the return of the C-shaped lever 110 to its normal position will move its lug off face 124 and allow the lever part 116 to snap into its normal position by spring 117. The face 123 of lever 113 will thus move into abutting relation with the lug 111 of arm 110.

Although the invention is described as embodied in a decimal or denominational tabulating mechanism, having therefore a plurality of keys and corresponding reeds, it will be understood that the invention is also advantageous in column tabulators having only a single key and tabulator reed. In fact, the tabulator mechanism herein set forth as controlled by the palm tabulator key is in effect a column tabulator mechanism. It will also be understood that, while it is desirable to employ a reed-selecting mechanism based on the permutation principle as herein described, the selection of said reeds may be effected by conventional means, that is, by a train of mechanism for each decimal tabulator key, individually connecting said key to the corresponding reed, as also set forth in the Yaeger patent.

What is claimed is:

1. In a typewriter tabulating mechanism, a plurality of reeds each projectable to a position for arresting the carriage in a tabulating run, spring means to project said reeds, means including keys to selectively release said reeds for projection, means including a motor for power-retracting the projected reeds, said retracting means including a movable member normally obstructing projection of said reeds, control means for said motor including an element movable to on and off positions, and means, rendered effective upon movement of said control element to off position, to obstruct operation of said retracting means and thereby hold its member in the reed-obstructing position preventing effective projection of said reeds while said control element is in the off position.

2. In a typewriter tabulating mechanism, a plurality of reeds each projectable to a position for arresting the carriage in a tabulating run, spring means to project said reeds, means common to all of said reeds and including a motor for power-retracting the projected reeds, means normally blocking operation of said retracting means, key-operated means to selectively release said reeds for projection and disable said blocking means, control means for said motor includ-

ing an element movable to on and off positions, and means effective upon movement of said control element to the off position to prevent operation of said power-operated retracting means although released by disablement of said blocking means.

3. In a typewriter tabulating mechanism, a plurality of reeds each projectable to a position for arresting the carriage in a tabulating run, spring means to project said reeds, a bail frame common to all of said reeds and normally disposed to retain said reeds retracted and adapted to be displaced incident to projecting a reed, power means including a motor and an operating train to said bail frame to rock said frame and thereby retract the projected reed, control means for said motor including an element movable to on and off positions, a device normally free of and adapted to obstruct operation of said operating train, and means effective upon moving said control element to the off position to cause said device to obstruct the operating train and thereby prevent projection of said reeds by retaining the bail frame in its normal position.

4. In a typewriter tabulating mechanism, a plurality of reeds each projectable to a position for arresting the carriage in a tabulating run, spring means to project said reeds, means including a set of keys to releasably retain said reeds retracted and selectively release said reeds for projection, a bail frame common to all of said reeds and normally disposed to retain said reeds retracted and adapted to be displaced incident to projecting a released reed, power means including a motor and an operating train to said bail frame to rock said frame and thereby retract the projected reeds, means normally blocking operation of said operating train and rendered ineffective by operation of said keys, control means for said motor including an element movable to on and off positions, a device normally free of and adapted to obstruct operation of said operating train, and means effective upon moving said control element to the off position to cause said device to obstruct the operating train although the latter is released by disabling the blocking means.

5. In a typewriter tabulating mechanism, a tabulator reed urged to project to a position for arresting the carriage in a tabulating run, releasable means to retain the reed retracted, a key-operable device normally blocking said retaining means and effective upon operating said key to release the retaining means and thereby release the reed for projection, said retaining means, upon being reversely operated after release, being adapted to retract the projected reed, power means including a motor to reversely operate said reed-retaining means and thereby retract the projected reed, control means for said motor including an element movable to on and off positions, and means, effective with said control element in the off position, to obstruct the reed-releasing action of said reed-retaining means.

WALTER T. SAGNER.
